CLAIM

The ornamental design for a ratchet buckle as shown and described.

DESCRIPTION

FIG. 1 is a front, right and top perspective view of a ratchet buckle, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and top perspective view of a second embodiment of a ratchet buckle.

FIG. 10 is a rear, left and bottom perspective view of the second embodiment of the ratchet buckle of FIG. 9.

FIG. 11 is a front elevation view of the second embodiment of the ratchet buckle of FIG. 9.

FIG. 12 is a rear elevation view of the second embodiment of the ratchet buckle of FIG. 9.

FIG. 13 is a left side elevation view of the second embodiment of the ratchet buckle of FIG. 9.

FIG. 14 is a right side elevation view of the second embodiment of the ratchet buckle of FIG. 9.

FIG. 15 is a top plan elevation view of the second embodiment of the ratchet buckle of FIG. 9; and,

FIG. 16 is a bottom plan elevation view of the second embodiment of the ratchet buckle of FIG. 9.

The broken lines depict portions of the ratchet buckle that form no part of the claimed design.
